UNITED STATES PATENT OFFICE.

HARRY L. RIDER, OF OIL CITY, PENNSYLVANIA.

ELECTRICAL SIGNALING SYSTEM FOR RAILWAYS.

No. 870,466.

Specification of Letters Patent.

Patented Nov. 5, 1907.

Application filed October 26, 1906. Serial No. 340,766.

To all whom it may concern:

Be it known that I, HARRY L. RIDER, a citizen of the United States of America, residing at Oil City, in the county of Venango and State of Pennsylvania, have invented certain new and useful Improvements in Electrical Signaling Systems for Railways, of which the following is a specification, reference being had therein to the accompanying drawing.

This invention relates to electrical signaling systems for railways, and its primary object is to provide means for protecting trains from collision by means of electrically-operated signals located both in front and in rear of the train.

A further object of this invention is to prevent the possibility of collision by reason of the failure of the engineer to observe or obey a danger signal, by providing means for automatically applying the brakes and stopping the train in case the latter is not stopped by the engineer in obedience to signal.

The invention comprises means for effecting these objects including track instruments of novel construction and various details of construction and combinations of devices, all of which will be fully described hereinafter in connection with the accompanying drawing which forms part of this specification, and defined in the appended claims.

In the drawing, Figure 1 is a diagram illustrating the electrical connections employed with the improved system, Fig. 2 is a side elevation of one of the signal posts and semaphore arms, Fig. 3 is a vertical sectional view of one of the track stop-plates employed, Fig. 4 is a partial side view of a locomotive carrying my improved valve and contact device, Fig. 5 is a side elevation partly in section of the track stop-plate and its connections, Fig. 6 is a front elevation of the same, Fig. 7 shows one form of connecting means between a signal post magnet and the signal blade rod and balance weight lever, Fig. 8 illustrates a modified construction of this connecting mechanism, Fig. 9 is a view partly in side elevation and partly in vertical section of the valve mechanism carried on the locomotive and adapted to be operated by the track stop-plates, Fig. 10 is a detail showing means for adjusting the stop-plate rod connections. Fig. 11 is a sectional view of the equalizing valve with its pistons in normal position, Fig. 12 is a similar view showing the pistons in their lowered position, Fig. 13 is a view in perspective and partly in vertical section of the cylinder of the equalizing valve, Fig. 14 is a view partly in section and partly in elevation of the lower portion of the air cylinder, and Fig. 15 is a diagram of one section of track.

I employ a track stop-plate at the entrance and exit ends of each section, the specific construction of which will be hereinafter described. These stop-plates are adapted to be struck by a lever depending from a valve casing carried by the locomotive at any convenient

point, to automatically operate the air brake and stop the train. The construction of this feature of the improvement will also be described hereinafter.

The location of the signals and stop-plates and their electrical connections are shown in Fig. 1. The track is arranged in mile blocks or sections designated by the letters A, B, C, & D, but may be arranged in any fraction or any number of miles.

Assuming the sections B and C are occupied by trains, that on section B, traveling to the left and the one on section C to the right, the train on B would set a signal at a point a mile to the right of the post marked *a* and the train on C would set a signal at post marked *b*. At the same time the B train will operate a signal at the post marked *c* and the C train would set a signal at the post marked *d*. In other words each train simultaneously operates an advance signal and a rear signal, thus protecting itself from collision from either direction. Should both trains keep advancing, the first one to reach the end of the section on which it is traveling will be forced to stop at that point whether the engineer observed the signal or not. Thus the B train would stop at the point designated at *e* and the C train at the point *f*, and the two trains traveling toward each other could not approach each other nearer than one mile or the distance of one block or section.

The signals are operated by electric batteries 1, 2, 3, 4 and 5 located one at the end of each section. The circuit from the battery 2, for example, will be through the wires 6, 7, and 8 to the battery 5, through wire 9, to a stop-plate 10, thence to wire 11, signal post *b* and through wires 12, 13 and 14 to the rail 15, thence through the engine axle indicated at 16 to the rail 17, thence through wires 18, 19 and 20 to signal post 21, thence to wire 22 stop-plate *e* and wire 23 back to battery 2. The circuits from the other batteries are similarly connected.

Referring now to Figs. 3, 5 and 6, the numeral 24 designates a frame or housing supported between the ties of the track and inclosing a frame 24^a serving as a guide for the vertically movable stop-plate 26 formed with a head 27. The plate 26 is connected by a rod 28 to the core of a solenoid 29, the latter being connected in the signal circuit as already explained. In Fig. 10, I show a modification in which the rod connection 28 is threaded and adjustably connected to an internally threaded sleeve 29^a thus permitting the throw or movement of the track stop-plate to be varied.

In Figs. 7 and 8, I have shown the manner of connecting the signal blades and their balance weight levers. The signal post is designated by the numeral 30 and the signal blade 31 is pivotally secured thereto. A rod 32 connects the short arm of the signal blade, to one end of a lever 33, the opposite end of which is pivotally secured by a link 34 to a lever 35 fulcrumed upon a support 36, and secured to the core 37 of a signal

magnet or solenoid 38, a cushioning spring 39 being arranged below the link 34.

As a substitute for the signal blade connections shown in Fig. 7 the rod 32 may be pivotally connected to a lever 40 fulcrumed at one end upon a support 41 and pivotally secured at its opposite end to the core of the signal magnet. The weighted lever 42 fulcrumed on the post 30 and connected at 43 to the rod 32, serves as a counter balance for the signal blade.

10 At any convenient point upon the locomotive is arranged a valve casing 44 from which depends a bulb 45 carrying a lever 46 formed with a semi-circular head 47, bearing against a similar head 48 on the end of a piston rod 49 extending into the bulb 45, and having a coil spring 50 arranged thereon between suitable collars.

The train pipe is cut at some convenient point on the engine, probably below the cab floor would be most convenient, and the valve casing 44 is connected into 20 the train pipe.

Within the casing 44 are two pistons 51 and 52, the lower one 51 being connected to the rod 49 while a rod 53 extends centrally through the upper piston 52 and into a central guide opening 54 formed in the lower 25 piston 51. A coil spring 55 encircles the rod 53 of the upper piston.

The casing 44 is formed on one side with an air passage 55^a to convey air from the train pipe to the space 56 between the pistons, and the lower piston is formed 30 with a port 57 communicating with an air passage 58 formed in the casing communicating with the space 59 above the upper piston.

In the upper right hand side of the upper piston is a leak port extending out at the right side directly opposite 35 the exit to atmosphere, and just above the bottom of the upper piston is another exit to atmosphere for commencing the leak.

The operation is as follows:—The plunger 29 of the solenoid is drawn upward by the current, pushing the 40 connecting rod 28 and stop-plate 26 upward. The plate 26 is then in position to serve as an obstruction to the trip lever 46 on the engine. This action is effected automatically by the current when the wheels and axle of the engine complete a circuit between the 45 rails. As the engine carrying the trip lever goes forward over the stop-plate, the plate presses the trip backward thus removing the upper end of said trip lever as an obstruction to the piston rod 49 above it allowing the piston 51 to drop down permitting the 50 air to pass through the cylinder 44. When the rod 49 is down air is permitted to flow from the space between the pistons 51 and 52 to the port 58 on the left side of the cylinder to the top of the cylinder to set the brake.

In running or normal position, the pistons 51, 52 of 55 the valve are in the position shown in Fig. 11 of the drawings, the piston 52, it will be observed just neatly uncovering port 55^a, and the piston 51 closing port 58, permitting air from the train pipe to enter the space between the pistons 51, 52 in the center of the cylinder. In this position, the operation of the brakes by the engineer from the cab is not affected.

The connection between port 55^a and port 58 is made by the lower piston dropping down below the entrance of port 58, which drop is permitted by lateral 60 movement having been imparted to trip lever 26,

moving the segment head 47 thereof so that piston 51 and piston rod 49 is permitted to drop. When this drop occurs, the air in the center of the cylinder between the pistons 51, 52, leaves the center by way of port 58, the latter having been uncovered by the dropping of piston 51. The air entering the port 58 flows to the top of the cylinder above the piston 52, and forces this piston down, so that it closes port 55^a as seen in Figs. 12 and 14 of the drawings, the air being retained above the piston 52 and as the cylinder will hold sufficient air above the upper piston when drawn from the train pipe, the brakes are caused to be set throughout.

The reason the air is permitted to pass to the top of this cylinder is two-fold. First I remove a sufficient quantity of air to set the brakes, and secondly I do not allow it to pass out to the atmosphere but confine it within the top of the cylinder where it is utilized as when the pressure is the same above the upper piston as between the pistons the upper piston moves down and covers the port 55^a through which the air was drawn from the train pipe to set the brakes. And before the brakes can be released, this air above the upper piston must leak out at the port 55^a just above the upper piston at the right. To permit the air to escape to the atmosphere would entail a loss of more than seven pounds pressure, and any reduction exceeding seven pounds would be a clear loss.

Referring now to Fig. 15 of the drawing, which shows one section of track in full lines, and two adjoining sections in dotted lines, a train entering the section H completes a circuit across the rails through the locomotive axle. The current is from the battery 75 to the wires 76 and 77, signal post 78, wire 79, stop-plate 80, battery 81 wires 82 and 83, rail 84, through axle of locomotive 85 to rail 86, wires 87 and 88, signal post 89, wire 90, stop-plate 91 and wire 92 back to the battery 75. The train air pressure is between the two pistons. When the trip lever 46 strikes the track stop-plate said lever is turned to one side or the other, permitting pressure of the spring just above on the rod 49 together with the weight of the piston and the expansive power of the compressed air to lower the piston 51 to the bottom of the casing. This allows the compressed air between the pistons to escape through the port 57 when it is opposite the air passage 58, into the 110 passage 58 and thence upward into the space above the upper piston forcing down said upper piston, thus closing the lower end of the train air passage 55^a and preventing any further leakage of air. The brake will set by the quantity of air permitted to flow around 115 through to the top of the casing and the expansion of the air forces the upper piston down. When it is down it rests upon the lower piston with the leak port in the upper right side of the upper piston just opposite the seat.

When the air leaks out sufficiently to reduce the pressure, the engineer can get down from the cab and turn the trip lever 46 back to a vertical position, thus raising the lower piston, compressing the upper spring 55 which in turn starts the upper piston up permitting 120 the air from the pump which will now be running to again recharge the train pipe with its normal pressure and running into the space 56 between the two pistons forcing one down and the other up to their normal positions.

At and opposite the air entrance to port 58 at the bottom of said port, a screw plug is inserted in and extending through the casing 44 and entering the air passage 58, to regulate the flow of air from the space 56 through

5 port 58 to space 59 in order to produce as may be deemed advisable either ordinary service application, a quick-service, or emergency application of the brakes, the service application being sufficient at all times with this device.

10 It will be apparent from the foregoing description that the improvement not only affords effective signal protection for both the front and rear of a train, but the further security of automatically stopping the train in case the signals are not seen or are ignored by 15 the engineer.

This device also affords protection against collision with a train on a siding by running into the switch should it have been left open by the train standing thereon; also prevents destruction of train by running 20 into an open-drawbridge; also prevents side-wiping of a train standing on a side-track but not in sufficiently far to clear a passing train. This arrangement or device also affords protection against a train being derailed and wrecked by running into an open main line 25 switch. The main line switches are so arranged in connection in the circuit that they will set the signals and track-stops one mile each side of the section, in which the open switch is located.

30 This arrangement or device is applicable to single track as well as double track and if signal blades are desired, both blades for single track can be attached to same signal post on opposite sides.

This device will prevent the forward portion of a train broken in two from running away and leaving 35 the rear portion standing on the main line, as the rear portion will cause the signal and track stop ahead of the train on the next succeeding section to be set at danger, stopping the train when the engine reaches said track stop. Similarly, the rear portion will cause a danger 40 signal and the track stop to be set back of said rear portion on the next adjoining section, stopping any train following approaching nearer to the dead portion of train ahead than one mile.

What I claim and desire to secure by Letters Patent, 45 is:—

1. In an electrical signaling system, the combination with signals and electric circuits therefor, of track stop-

plates included in said circuits and means carried by a locomotive adapted to strike said plates, a valve casing also carried by the locomotive, two pistons within said 50 casing, and means for operating said pistons to set the air brakes, and to release said brakes.

2. In an electrical signaling system, the combination with signals and electric circuits therefor, of track stop-plates, electrical means for operating said plates, a contact lever carried by the locomotive, a valve casing carried by the locomotive, pistons within said casing, and ports and air passages in said pistons and casing for causing a leakage of air when said contact lever is operated.

3. In an electric signaling system, the combination with track signals and electric circuits therefor, and track stop-plates included in said electric circuits, of means for applying the air brakes of a train comprising a valve casing carried by the locomotive, two vertically-movable pistons within said casing, and a pivoted lever normally holding said pistons elevated and adapted to be operated by said stop-plates to permit the pistons to drop and allow the passage of air to apply the brakes.

4. Electrically-operated means for actuating railway 70 signals and mechanically-operated means for applying the brakes of a train, comprising track signals, electric circuits therefor, and track stop-plates included in said circuits, a valve casing carried by the locomotive normally in open communication with the air supply of the air 75 brakes, two pistons in said valve casing, and means also carried by the locomotive for normally holding said pistons in position to respectively uncover the inlet port to the valve casing and cover the outlet port of said valve casing and operated by said track stop-plates to permit 80 the pistons to move into position to cover the air inlet port of the valve casing and uncover the air outlet port thereof.

5. Electrically-operated means for actuating railway 85 track signals and mechanically operated means for applying the brakes of a train, comprising track signals, electric circuits therefor, and track stop-plates included in said circuits, a valve casing carried by the locomotive having an inlet and an outlet port, the inlet port being normally 90 in communication with the air supply and the outlet port normally closed, two pistons in said valve casing, and means also carried by the locomotive for normally holding said pistons in position to respectively uncover the inlet port to the valve casing and cover the outlet port thereof, said means operating by said track stop-plates to permit 95 movement of the pistons to uncover the outlet port of the valve casing and thereafter close the inlet port thereof, substantially as described.

In testimony whereof I affix my signature in the presence of two witnesses.

HARRY L. RIDER.
